Primary Examiner — Kevin K Rudzinski*Assistant Examiner* — Paul D Bohannon*(74) Attorney, Agent, or Firm* — Troutman Pepper
Hamilton Sanders LLP(57) **CLAIM**

I claim the ornamental design for a chair, as shown and described.

DESCRIPTIONFIG. 1 is an upper perspective view of a chair;
FIG. 2 is a lower perspective view of the design shown in FIG. 1;FIG. 3 is a front plan view of the design shown in FIG. 1;
FIG. 4 is a rear plan view of the design shown in FIG. 1;
FIG. 5 is a left side plan view of the design shown in FIG. 1;

FIG. 6 is a right side plan view of the design shown in FIG. 1;

FIG. 7 is a top plan view of the design shown in FIG. 1; and,
FIG. 8 is a bottom plan view of the design shown in FIG. 1.
The broken lines shown in the drawings are for the purpose
of illustrating portions of the article and form no part of the
claimed design. The shade lines shown represent surface
shading and not surface ornamentation, color, or material
type.**1 Claim, 8 Drawing Sheets**(56)
